PEDESTAL

Gustav H. Koch, Springfield, Mass., assignor to Westinghouse Electric & Manufacturing Company, East Pittsburgh, Pa., a corporation of Pennsylvania

Application May 8, 1943, Serial No. 486,139

6 Claims. (Cl. 248—194)

My invention relates to air translating apparatus and, more particularly to a relatively large fan of the floor-supported, pedestal-mounted type, in which the fan motor unit and the fan guard are mounted on the top end of the supporting column, with a base secured to the lower end of the supporting column.

Conventionally, the supporting column is rigidly secured to a relatively large base to insure stability, and, the combined weight of the motor fan assembly, column and base is more than can be lifted by an average person conveniently or without undue strain. Dragging a fan of this type from one location to another may cause damage to the fan and to the surface over which it is dragged.

Furthermore, with the supporting column rigidly secured to a base, it is difficult to "wheel" the entire fan structure on the rim of the base. This is due to the fact that the relatively large fan blades and their guard will also rotate with the supporting column, thus making it necessary for the operator to keep at a safe distance to avoid being hit by the fan guard, and to exercise special care to prevent the guard 16 causing damage to walls or articles of furniture. Also, to rotate a rigidly secured assembly, it is necessary to rotate the supporting column itself and this can only be done intermittently and by repeated grasping and ungrasping of the column with one or both hands.

Furthermore, it is often necessary to adjust a fan of this character to blow in a certain direction and, where the supporting column is rigidly secured to the base, the entire apparatus must be lifted and placed at the correct angle.

One object of my invention is to produce an improved fan of the type set forth.

A further object of my invention is to produce a fan which may be easily moved from one location to another without being lifted off the floor, and without any great effort or strain.

A still further object of my invention is to produce a fan which may be moved from one location to another without any damage to the fan itself or to the floor or other surface over which it is moved.

A still further object of my invention is to produce a fan of the type set forth which may be readily moved from one location to another and which has a pleasing appearance.

To overcome the disadvantages above set forth, I provide a fan having a base which is rotatable relative to the supporting column. To move the fan from one location to another, the fan

is tilted so that the base contacts the floor only on a peripheral tread portion and turns freely as a wheel. Provision is also made for holding the column and the base against relative rotation when the fan is in the desired position.

These and other objects are effected by my invention as will be apparent from the following description and claims taken in connection with the accompanying drawings, forming a part 10 of this application, in which:

Fig. 1 is a front elevational view of a fan embodying my invention;

Fig. 2 is an enlarged, vertical sectional view of the lower portion of the fan showing the cover 15 in engagement with, and preventing, the rotation of said base;

Fig. 3 is a view similar to Fig. 2 showing the cover out of engagement with and permitting rotation of said base;

Fig. 4 is a perspective view illustrating the manner in which the fan may be easily moved from one location to another;

Fig. 5 is a view similar to Fig. 1 and showing an alternate form of construction;

Fig. 6 is an enlarged vertical sectional view of the lower portion of Fig. 1 showing the base in nonrotating position;

Fig. 7 is a view similar to Fig. 6 showing the base in freely rotating position;

Fig. 8 is a fragmentary sectional view taken on line VIII—VIII of Fig. 7;

Fig. 9 is an enlarged view of the lower right-hand portion of Fig. 6; and,

Fig. 10 is a perspective view of the lower right-hand portion of the cover, certain parts being omitted to show details of construction.

Referring to the drawings in detail, I show a fan including a motor 12, blades 14 and a guard 16, constituting an assembly which may be secured in any usual manner to a column or pedestal 18. The column 18 is preferably of a vertically adjustable type, the adjusting mechanism 20 being only diagrammatically shown. The motor 12 is supplied with electric current 40 by suitably disposed conductors. The parts thus far described may be of any desired conventional structure and form no part of the present invention.

According to my invention, I make the supporting column 18 rotatable with respect to the base of the fan. This is accomplished by a construction which includes a sleeve 22 rigidly secured to the column 18 and having an upper reduced portion 24. The sleeve 22 is rotatably connected to a base 26 by vertically spaced ball bear-

ing means 28 and 30. The ball bearing means 28 engages the lower portion of a boss 32, which is integral with, or rigidly secured to, the base 26, and the ball bearing means 30 engages an upper, reduced portion 34 of the boss 32. The outer portion or rim of the base 26 is deflected upwardly to form a tread portion 36 which is preferably provided with a rubber or other soft and frictional covering 38. By this construction, the fan can be tilted to about the position shown in Fig. 4 and wheeled on the tread portion 36 from one location to another, without being lifted off the floor. The covering 38 prevents damage to the periphery of the base 26 or to the surface over which it is moved.

In order to present a pleasing appearance and in order to prevent relative rotation of the base 26 and column 18, when the apparatus is stationary, I provide a locking and ornamental cover 40. The periphery of the cover 40 is preferably of a slightly smaller diameter than the base 26, measured at the edge or rim of the tread portion 36, so that, when the fan is tilted as shown in Fig. 4, the edge 41 of the cover 40 will not come in contact with the floor or other surface. The cover 40 is provided with a reduced neck 42 which is slidable vertically on the column 18. To the interior of the cover 40 are suitably secured, as at 44, one or more spring clips 45 having curved or cam portions 46 which are adapted to engage either an upper or a lower annular recess or notch 48 or 50, formed in the upper reduced portion 24 of the sleeve 22. The shape of the cam portions 46 with respect to the recess or notches 50 is such that when the cover 40 is forced into its lower position, the cam portions 46 of the spring clips 45, by engaging the lower correspondingly curved wall of the recess 50, clamp the bottom periphery 41 of the cover 40 snugly against the periphery 36, or the covering 38 thereof, if said covering is used. The frictional engagement of the periphery of the cover 40 with the periphery of the base, under pressure of the spring clips 45, locks the base 26 and column 18 against relative rotation. When it is desired to move the fan, the cover 40 is pulled upwardly to disengage the cam portions 46 from the recess or notches 50. The base is now freely rotatable and acts as a wheel support for the fan. In the upper position of the cover 40, the curved portions 46 of the spring clips 45 engage the upper recess 48 to prevent the cover from dropping until it is intentionally pressed into its lower position.

It will thus be seen that I have devised a novel fan which may be easily and conveniently moved from one location to another without lifting or dragging. It will also be seen that this is accomplished by simple and relatively inexpensive means which can be operated without any skill or special effort.

In Figs. 5 to 10, I show an alternate form of construction in which the spring clips 45 and notches 46 are omitted and in which the cover 40 is rigidly secured to the column 18 by a set screw or the like 54 passing through a hub or boss 56 which is integral with or rigidly secured to the cover 40. The base 26 is rotatable with respect to the hub 56 on the bearings 28 and 30 in the same manner as that described in connection with Fig. 2. It will be noted that in the present construction, the periphery 36 of the base 26 is not deflected so that the base 26 is flat throughout, and that the cover 40 is at all times spaced from and out of contact with the base 26.

In order to prevent free rotation of the base 26,

I provide a spring 58 which is secured to a portion of the hub, as at 60, and the outer end 62 which normally bears down upon the periphery 36 of the base 26, as shown in Figs. 6 and 9. In order to disengage the spring 58 from the base 26, I provide a flexible connection such as the ball chain 64, one end of which is secured to the spring 58, as at 66, and the other end of which extends through a key-hole shaped opening 68 in the cover 40. To the other end of the chain 64 is secured a grip or handle portion 70, which may be in the form of a ring, but the size and shape of which are optional. The opening 68 is provided with a reduced portion or slot 72 which is wide enough to receive the links 74 connecting the balls of the chain but which is too small for passage of one of the balls themselves. Registering with the outer or movable end of the end 62 of the spring 58 is a recess 76 formed in the periphery of the cover 40.

Operation—Figs. 5 to 10

Normally, the spring 58 presses down against the periphery of the base 26 so that it prevents free relative rotation of the base and the column 18. If it is desired to move the fan from one location to another, the operator pulls upwardly on the chain 64 until the end 62 of the spring 58 is out of engagement with the base 26, as shown in Fig. 7. In order to retain the spring in this position, the chain is engaged in the reduced portion 72 of the opening 68. The fan may now be wheeled on the periphery of the base from one location to another, or the column 18 may be rotated relative to the base to set the fan to the desired angle. To return the spring to the position shown in Fig. 9, the operator releases the link 74 from the reduced portion 72 and allows the chain to drop down through the opening 68 to release the spring 58.

It will be seen that this alternate construction possesses all the advantages possessed by the construction illustrated and described in connection with Figs. 1 to 4.

In both forms of construction the motor 12 is energized by an electric cord 80 which enters the standard 18 through an opening 82 near the upper thereof and which extends downwardly through the standard 18 and emerges through an opening 84. The opening 84 may be provided in the cover 40 or at a suitable point in the lower portion of the standard, it being necessary that the structure be such that the cord 80 will not twist and turn as the fan is wheeled about the base 26.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are specifically set forth in the appended claims.

What I claim is:

1. A pedestal for supporting an electric device including a column, and a base for supporting said column, means for rotatably connecting said base to said column, whereby said base serves as a wheel support on which said pedestal may be moved from one location to another, and an electric conductor for energizing said device, said conductor extending through said column and being so constructed and arranged as to be non-rotatable with the rotation of said base with respect to said column.

2. The structure recited in claim 1 together with means for normally holding said base against rotation.

3. A pedestal comprising a column and a base for said column, and means for assembling said base to said column comprising a sleeve fixedly secured to said column, means for rotatably connecting said sleeve to said base, and a combined cover and locking member slidable on said column into an operative position in engagement with, and preventing the rotation of said base, and into an inoperative position spaced from and permitting rotation of said base.

4. The structure recited in claim 3 in which said sleeve is provided with spaced recesses, and in which a spring clip is carried interiorly of said member for detachably engaging either of said recesses.

5. A pedestal comprising a column, a base for supporting said column, means for rotatably con-

necting said base to said column, whereby said base serves as a wheel support on which said pedestal may be moved from one location to another, and means for permitting or preventing rotation of said base comprising a spring carried by said column and engaging said base and means for disengaging said spring from said base.

6. A pedestal comprising a column, a base for supporting said column, means for rotatably connecting said base to said column, whereby said base serves as a wheel support on which said pedestal may be moved from one location to another, locking means for preventing rotation of said base relative to said column, a cover concealing said base and said locking means, and exteriorly accessible means for disengaging said locking means to permit rotation of said base and column.

GUSTAV H. KOCH.
